STABILIZER AND EDGE SUPPORT FOR COIL SPRINGS

Murray J. Rymland, Baltimore, Md.

Application March 18, 1955, Serial No. 495,309

14 Claims. (Cl. 5—260)

This invention relates to spring cushioning assemblies, and more particularly to spring assemblies of the type containing a large number of helical coil springs, associated and interconnected in a predetermined spaced relation to one another. Assemblies of this type are described in my prior Patent No. 2,630,586, granted March 10, 1953, and in my co-pending application, Serial No. 384,874, filed October 8, 1953, now Patent No. 2,791,783, granted May 14, 1957; and the present invention represents a variation and improvement on the structures therein claimed.

Among the general objects of the present invention, it is contemplated to provide a spring cushion assembly which is particularly well adapted to withstand repeated distortions of the edge portions by a locally applied compressive force, such as the weight of a body, and to provide an assembly of simplified, durable, and inexpensive construction wherein permanent distortion or distortion of the edge portion is less likely to occur than in the spring cushion assemblies heretofore known and used.

A particular object of this invention is to provide means for bolstering and strengthening the edge portions of a spring cushion assembly constructed with rows and files of prearranged coil springs.

It is a further object of this invention to provide a spring cushion assembly having its edges formed and arranged in a manner adapted to prevent padding or filling material from entering into the component springs thereof, and particularly to prevent such entry through the voids or cleavages defined by the exteriorly facing portions of the outside rows of coil springs.

It is another object of this invention to provide a spring cushion assembly in which the edge portions of the assembly, defined by the outside rows of coils, are provided with special means for resisting the localized stresses which are frequently placed upon the edges of spring cushion assemblies in their normal domestic uses.

It is another object of this invention to provide a spring assembly unit adapted for semi-automatic and automatic assembly.

Further objects of the invention will be in part obvious and in part pointed out hereinafter.

The invention, and novel features thereof, may best be made clear from the following description and the accompanying drawings, in which:

Figure 1 is a fragmentary plan view of a spring cushion assembly constructed according to the present invention;

Figure 2 is an elevational view, taken partially in section, along line 2—2 of Figure 1;

Figure 3 is an elevation view, taken along line 3—3 of Figure 1;

Figure 4 is a perspective view of a continuous tie wire having its end portions formed as a sear spring; and

Figure 5 is a perspective view of a tie wire embodying the planar edge support as defined in this invention.

Referring to the drawings in detail, a spring cushion assembly comprises a plurality of component helical coil

2

springs 10 constructed of wire in the conventional form as illustrated in Figures 1, 2, and 3. The springs are arranged in rows 12, 14, and files 16, 18, and each row of springs is aligned and arranged with an arcuate portion of the end convolution of each spring overlapping a corresponding portion of an adjacent spring in the same row, whereby one such portion becomes an overlying arcuate portion 20, and the other becomes an underlying arcuate portion 22, and a space 24 is provided between the overlapped portions.

To fix adjacent rows in the desired parallel spaced relationship, and to insure that the corresponding coils of adjacent rows are properly arranged in files 16, 18, a plurality of tie wires 26 extend transversely of the rows along the lines of overlap between the coils, that is, along the lines of overlap between the files. Each tie wire 26 is provided with a plurality of pairs of spaced depressions 28, each pair of depressions being separated by an upwardly projecting insert 30 therebetween, as best illustrated in Figures 1, 2, 4, and 5. When positioned in the assembly, each pair of depressions 28 partially embraces the intersecting sections of an overlapping pair of arcuate portions 20, 22, and the intermediate insert 30 projects into the space 24 therebetween. As will be readily understood, the pairs of depressions 28 are spaced along the length of the tie wires 26 to suitably space from each other, adjacent rows 12, 14, of component springs, the structure illustrated in Figure 1 being merely a partial view of the two spring rows 12, 14, and, therefore, two spring files 16, 18, of the overall assembly.

In my prior patent referred to, and in my prior application referred to, the overlapping arcuate portions of the adjacent springs are secured to each other and to the tie wire inserts in some particular and specialized manner. I have chosen to illustrate the present invention as being equipped with the individual clamp members 32 described in detail in my prior patent, but it should be clearly understood that these elements may be fixed, or joined, together by any other suitable means.

Referring more particularly to Figure 1, it will be seen that the outside row 12 of coil springs 10 defines the edge 34 (here shown as a phantom line) of the complete coil spring assembly. Inasmuch as the edge line is actually a line tangent to the end convolution of the outside row 12 of the coil springs 10, it will be seen that some portions of the edge are open or unsupported. Inasmuch as the end convolutions of the coil springs are generally circular, it will be readily seen that the end portions of the coil spring give only a limited support to the edge portions of the assembled coil spring assembly and that there is a deep, roughly triangular, cleavage 35 defined by adjacent end portions of the end convolutions of the coil springs and by the edge line 34.

In practice, the coil spring assembly is covered with a padding or filler of fabric or other material and it has been found desirable to provide a means for providing a support for the padding, fabric, or filler, which will be disposed directly above this cleavage. It is well known that the end or edge portions of a spring cushion assembly, whether it be used in a mattress, seat cushion, or the like, frequently receives a disproportionate amount of the weight borne by the complete spring cushion assembly. While the manufacturers of mattresses and the like frequently urge their customers to refrain from sitting on the edge of a mattress, it is nevertheless well known that such a practice is not easily discouraged and that it is quite usual for the edge of the mattress to sag and become lumpy and deformed from such misuse. This is especially true if a spring cushion assembly is formed without a heavy border or edge of heavy strap material. Such sagging occurs when the fabric, padding, or cushioning

material is allowed to slip down into the open area defined by the cleavage between the outside or exteriorly facing portions of the coil springs of an outside row.

Referring more particularly to Figures 1 to 5, it is within the contemplation of this invention to extend the transverse tie wire 26 outwardly beyond the overlap of the outside row 12 and to then transversely bend the tie wire to define a plane 36 which is substantially co-planar with the planes defined by the end convolutions of the coils 10. It should be here stated that inasmuch as the coils 10 overlap at 20, 22, the planes defined by the end portions of the coil springs are not precisely co-planar but only substantially co-planar, but the difference between these planes is ordinarily nominal when the spring cushion assembly is in its relaxed position and may be considered, for purposes of description, as negligible.

While the end of the tie wire 26 may be transversely bent into any of a wide variety of shapes to provide a planar edge support means, I have, in a preferred embodiment, bent the tie wire to form an isosceles triangle having its base extending along a line substantially identical with the edge line 34, and with the triangle so proportioned and dimensioned as to substantially fill the cleavage 35. As best shown in Figure 1, such a configuration provides an edge which is a substantially straight and continuous line 34. The tie wire may be provided with a triangular end before it is joined with the coil springs in the coil spring assembly, and such a preformed tie wire is shown in Figure 5.

While the use of the triangular or delta shaped planar edge support on the end of a tie wire extending transversely of the rows along the lines of overlap between the files will serve to prevent a displacement of the fabric, filler, or padding, when the edge of the spring cushion assembly is subjected to a downwardly directed force, such as by the weight of a body disposed on a completed mattress, spring cushion, or the like, I have also found that there are several additional advantages in providing a supplemental or ancillary spring means to aid in the support of the edge portion and to resiliently resist relative movement between two opposite edges of the spring cushion assembly. That is to say, while the use of the delta or triangular ends of the tie wires does serve to prevent a displacement of the fabric filler, or padding, into the interior of the material, it does not, in itself, form a means for resisting relative movement of one edge support toward another and opposite edge support when, for example, someone sits on the edge of the mattress.

It has long been considered desirable for a mattress or other spring cushion assembly to have additional support or stabilizing structure along its edge portions and this has been accomplished, for example, by using heavier and stronger springs in the outside rows, that is, the rows extending along the edge. It will be readily seen that the use of different types, sizes, or weights of coil springs in the mattress or spring cushion assembly serve to complicate the process of assembly by automatic machinery and hence adds to the final cost of the structure. It is, therefore, within the contemplation of this invention to provide an edge stabilizing means which can be used in connection with a mattress, or other spring cushion assembly, made up of a series of identical coil springs arranged in rows and files, as described herein above.

While it has been the previous practice to provide the spring cushion assembly with a plurality of tie wires arranged in pairs, one above the other, on opposite planar sides of the spring cushion assembly, it is within the contemplation of this invention to provide a plurality of tie wires which are formed as a unitary structure to transversely circumscribe the entire spring cushion assembly. As shown in Figure 4, the continuous tie wire will have a roughly rectangular shape and will be made up of two legs 40, 42, extending transversely of the rows of coils 10 in a parallel spaced relationship, the spacing between these

legs being substantially identical with the distance between the end convolutions of the coils when the latter are in a relaxed position. The transversely extending legs 40, 42, are formed with the spaced depressions 28, as described hereinabove, and are joined, one to the other, by the end portions, generally indicated at 44. Each end portion of the tie wire is formed as a reinforcing or stabilizing edge spring, as shown, having two legs 46, 48, each of which makes a tangential junction with a cylindrical coil spring 50.

While I here speak, for purposes of exactness of description, of the transversely extending legs 40, 42, of the spring legs 46, 48, and the cylindrical coil spring 50, as different elements, it should be clear that I envision a single continuous tie wire 26 embodying all these elements as component portions thereof.

It is also within the contemplation of this invention that the ends of the longitudinally extending legs 40, 42, of the continuous tie wire should be formed with the delta-shaped edge support 36, or other plane defining configuration, as described hereinabove, before being turned inward to form the spring legs 46, 48, respectively.

Referring to Figures 1, 2, and 3, it will be seen that the continuous tie wire 26 extends transversely of the rows, along the lines of the overlap of the files, with one leg extending along one planar surface 52 of the spring cushion assembly and with the other longitudinal leg extending along the opposite planar surface 54 of the spring cushion assembly. The transversely extending leg portions of the continuous tie wire extend outwardly beyond the overlap of the outside row 12 of coils before turning inward to define the spring portions 44 of the tie wire. As best shown in Figure 3, it is within the contemplation of this invention that the coil springs 10 are of the double helix variety so that the cylindrical coil spring 50 of the spring 44 will not engage the inner convolutions of the coil springs 10, located on either side thereof. However, it should be evident that the particular disposition of the plane defined by legs 46, 48 of each spring 44 may be varied from that shown, as desired. For example, the legs 46, 48 may be arranged so as to be substantially co-planar with the edge plane at 34.

Referring more particularly to Figure 2, it will be readily seen that the spring portion 44 of the continuous tie wire 26 will serve to resiliently resist any relative movement between two opposite lateral edges 34, 58, of the spring cushion assembly, and, as such, acts to supplement the outside row of coil springs.

In Figure 1, the lower delta 36' is illustrated as projecting outwardly a slight distance beyond the upper delta 36. This is shown merely to illustrate the identical configuration of the two deltas or triangles. In practice, they are disposed in exactly corresponding positions.

It should be clearly stated that it is entirely within the contemplation of this invention to use the reinforcing or stabilizing edge spring 44 to bolster or aid the exterior row of coil springs by providing additional support for the edge of the spring cushion assembly in applications where, through the particular configuration of the structure involved, the use of the planar edge support means, defined by the transverse bending of the tie wire, is unnecessary.

Having described only a typical preferred form and application of my invention, I do not wish to be limited or restricted to specific details herein set forth but wish to reserve to myself any variations or modifications that may appear to those skilled in the art and falling within the scope of the following claims.

I claim:

1. A spring cushion assembly comprising a plurality of upstanding coil springs arranged in rows and files, the coil springs being arranged with each of their end portions overlapping the end portions of at least one other coil spring in the same row, a plurality of tie wires extending transversely of the rows along the lines of overlap

between the files, means securing each of said tie wires with the end portions of the coil springs of each of a plurality of rows, each of said tie wires extending beyond the overlap of an exterior row into the exterior cleavage defined by the end portions of the overlapping coil springs, each of said tie wires terminating in a free end disposed within said cleavage, said tie wires at said free ends being transversely bent to form a planar edge support means disposed within said cleavage.

2. A spring cushion assembly comprising a plurality of upstanding coil springs arranged in rows and files, the coil springs being arranged with each of their end portions overlapping the end portions of at least one other coil spring in the same row, a plurality of tie wires extending transversely of the rows along the lines of overlap between the files, means securing each of said tie wires with the end portions of the coil springs of each of a plurality of rows, each of said tie wires extending beyond the overlap of an exterior row into the exterior cleavage defined by the end portions of the overlapping coil springs, each of said tie wires terminating in a free end disposed within said cleavage, each of said tie wires at said free ends being bent to define a plane which is substantially co-planar with the planes defined by the ends of the coil springs, said bent portions of the tie wire forming a planar edge support means which substantially fills said cleavage.

3. A spring cushion assembly comprising a plurality of upstanding coil springs arranged in rows and files, the coil springs being arranged with each of their end portions disposed adjacent to and generally coplanar with the end portions of the remaining springs in the assembly, a plurality of tie wires extending transversely of the rows between adjacent files of springs and generally coplanar with the end portions thereof, each of said tie wires extending beyond an exterior row into the exterior substantially triangular shaped cleavage defined by the end portions of the adjacent coil springs, each of said tie wires being transversely bent to define a triangle which is substantially co-planar with the planes defined by the ends of the coil springs, said triangle forming an edge support means which substantially fills the triangular cleavage and forms a support for the edge portions of the fabric and padding disposed upon the spring cushion assembly.

4. The structure defined in claim 3 in which the base of said triangle defines a portion of an exterior edge of the spring cushion assembly, whereby the edge of the spring cushion assembly is a substantially straight and continuous line.

5. A spring cushion assembly comprising a plurality of upstanding coil springs arranged in rows and files, the coil springs being arranged with each of their end portions overlapping the end portions of at least one other coil spring in the same row, a plurality of tie wires extending transversely of the rows along the lines of overlap between the files, each of said tie wires transversely circumscribing said spring cushion assembly and having a first leg extending along one planar surface of the spring cushion assembly and having another leg extending in parallel spaced relation to the first leg along another planar surface of the spring cushion assembly, said legs extending beyond the overlap of an exterior row into the exterior cleavage defined by the end portions of the overlapping coil springs, said legs being transversely bent to form a planar edge support disposed within said cleavage, and each of said tie wires defining a reinforcing spring at at least one transverse end of the spring cushion assembly to resiliently resist relative movement between two opposite edges of the spring cushion assembly.

6. The structure defined in claim 5 in which each of said legs of the tie wires extends substantially to at least one edge of the spring cushion assembly and then extends obliquely inwardly towards the interior of the spring cushion assembly, to form said reinforcing spring.

7. The structure defined in claim 5 and further including means formed integral with said tie wire to maintain said tie wire in a fixed position relative to the end portions of the overlapping coil springs.

8. A spring cushion assembly comprising a plurality of upstanding coil springs arranged in rows and files, the coil springs being arranged with each of their end portions overlapping the end portions of at least one other coil spring in the same row, a plurality of tie wires, each of said tie wires continuously circumscribing said cushion assembly and having portions extending transversely of the rows along the lines of overlap between the files, said portions extending beyond the overlap of an exterior row into the exterior cleavage defined by the end portions of the overlapping coil springs, said legs being transversely bent to form a planar edge support disposed within said cleavage, each of said tie wires having another portion joining said transversely extending portions adjacent opposite lateral edges of the spring cushion assembly, said second mentioned portion defining spring means to resiliently resist relative movement between the two opposite lateral edges of the spring cushion assembly.

9. A spring cushion assembly comprising a plurality of upstanding coil springs arranged in rows and files, the coil springs being arranged with each of their end portions overlapping the end portions of at least one other coil spring in the same row, a plurality of tie wires, each of said tie wires continuously circumscribing said cushion assembly and having portions extending transversely of the rows along the lines of overlap between the files, said portions extending beyond the overlap of an exterior row, each of said tie wires having an end structure unitary therewith and joining said transversely extending portions adjacent the opposite lateral edges of the spring cushion assembly, said end structure including converging portions extending obliquely from the transversely extending portions to define a reinforcing spring to resiliently supplement the exterior row of coil springs in resisting relative movement between two opposite lateral edges of the spring cushion assembly.

10. A spring cushion assembly comprising a plurality of upstanding coil springs arranged in rows and files, the coil springs being arranged with each of their end portions disposed adjacent to and generally coplanar with the end portions of the remaining springs in the assembly, a plurality of tie wires, each of said tie wires continuously circumscribing said cushion assembly and having portions extending transversely of the rows between adjacent files of springs and generally coplanar with the end portions thereof, said portions extending beyond an exterior row into the exterior cleavage defined by the end portions of the adjacent coil springs, said tie wires being transversely bent to form a planar edge support means disposed within said cleavage, each of said tie wires having another portion joining said transversely extending portions adjacent opposite lateral edges of the spring cushion assembly, said second mentioned portion defining spring means to resiliently resist relative movement between the two opposite lateral edges of the spring cushion assembly.

11. A spring cushion assembly comprising a plurality of upstanding coil springs arranged in rows and files, the coil springs being arranged with each of their end portions overlapping the end portions of at least one other coil spring in the same row, a plurality of tie wires, each of said tie wires continuously circumscribing said cushion assembly and having portions extending transversely of the rows along the lines of overlap between the files, each of said portions extending beyond the overlap of an exterior row into the exterior substantially triangular shaped cleavage defined by the end portions of the overlapping coil springs, each of said tie wires being transversely bent to define a triangle which is substantially co-planar with the planes defined by the ends of the coil springs, said triangle forming an edge support means.

which substantially fills the triangular cleavage and forms a support for the edge portions of the fabric and padding disposed upon the spring cushion assembly, each of said tie wires having another portion joining said transversely extending portions adjacent opposite lateral edges of the spring cushion assembly, said second mentioned portion defining spring means to resiliently resist relative movement between the two opposite lateral edges of the spring cushion assembly.

12. A spring cushion assembly comprising a plurality of upstanding coil springs arranged in rows and files, the coil springs being arranged with each of their end portions overlapping the end portions of at least one other coil spring in the same row, a plurality of tie wires, each of said tie wires continuously circumscribing said cushion assembly and having portions extending transversely of the rows along the lines of overlap between the files, each of said portions extending beyond the overlap of an exterior row into the exterior cleavage defined by the end portions of the overlapping coil springs, said tie wires being transversely bent to form a planar edge support means disposed within said cleavage, each of said tie wires having another portion joining said transversely extending portions adjacent the opposite lateral edges of the spring cushion assembly, said second mentioned portion extending obliquely inwardly from the opposite edges of the spring cushion assembly to define a reinforcing spring to resiliently supplement the exterior row of coil springs in resisting relative movement between two opposite lateral edges of the spring cushion assembly.

13. A spring cushion assembly comprising a plurality of upstanding coil springs arranged in rows and files, the coil springs being arranged with each of their end portions overlapping the end portions of at least one other coil spring in the same row, a plurality of tie wires, 35

each of said tie wires continuously circumscribing said cushion assembly and having portions extending transversely of the rows along the lines of overlap between the files, each of said portions extending beyond the overlap of an exterior row into the exterior substantially triangular shaped cleavage defined by the end portions of the overlapping coil springs, each of said tie wires being transversely bent to define a triangle which is substantially co-planar with the planes defined by the ends of 5 the coil springs, said triangle forming an edge support means which substantially fills the triangular cleavage and forms a support for the edge portions of the fabric and padding disposed upon the spring cushion assembly, each of said tie wires having another portion joining 10 said transversely extending portions adjacent the opposite lateral edges of the spring cushion assembly, said second mentioned portion extending obliquely inwardly from the opposite edges of the spring cushion assembly to define a reinforcing spring to resiliently supplement the 15 exterior row of coil springs in resisting relative movement between two opposite lateral edges of the spring cushion assembly.

14. The structure defined in claim 13 in which the base of said triangle defines a portion of an exterior edge 20 of the spring cushion assembly, whereby the edge of the spring cushion assembly is a substantially straight and continuous line.
